UNITED STATES PATENT OFFICE.

JOHN W. HAUGHAWOUT, OF OMAHA, NEBRASKA, ASSIGNOR TO THE LESLIE BROTHERS MANUFACTURING COMPANY, OF PATERSON, NEW JERSEY.

ROTARY SNOW-PLOW.

SPECIFICATION forming part of Letters Patent No. 446,773, dated February 17, 1891.

Application filed May 21, 1890. Serial No. 352,605. (No model.)

To all whom it may concern:

Be it known that I, JOHN W. HAUGHAWOUT, of Omaha, in the county of Douglas and State of Nebraska, have invented a new and Improved 5 Rotary Snow-Plow, of which the following is a full, clear, and exact description.

The object of the invention is to provide a new and improved rotary snow-plow which is simple and durable in construction, specially 10 designed for use on railroads, and adapted to readily cut the snow and remove the same from the track at either side of the latter.

The invention consists of certain parts and details and combinations of the same, as will 15 be hereinafter fully described and claimed.

Reference is to be had to the accompanying drawings, forming a part of this specification, in which similar letters of reference indicate corresponding parts in all the figures.

20 Figure 1 is a sectional side elevation of the improvement. Fig. 2 is a front view of the same with parts in section. Fig. 3 is a plan view of the same with parts in section, and Fig. 4 is a perspective view of part of the 25 casing.

The improved rotary snow-plow A is mounted on the end of a car B, adapted to travel on the railroad-track and move forward or backward by a locomotive or other suitable 30 means. In the car B is mounted to turn in suitable bearings the longitudinally-arranged main driving-shaft C, supporting at its outer end a wheel D, mounted to turn in a suitably-constructed casing E, secured on the 35 front end of the car B, and provided on top with an outlet F, through which the snow is discharged to either side of the track, the said outlet being preferably provided with a suitable deflector, so as to change the direction 40 of the snow as desired.

The wheel D is provided with a back plate G, from which extends at right angles toward the front a series of radially-arranged paddles H, terminating at their inner ends a suitable distance from the center of the wheel, so as to form a central space I in the said wheel in front of the back plate G. The paddles H are preferably of wedge form, the apexes being placed innermost, as is plainly shown in 45 Fig. 2.

On the outer end of each of the paddles H

is held a self-reversing knife J, secured on a shaft J', arranged radially and mounted to turn in suitable bearings in the front end of the paddle H. When the wheel D is turned 55 in one direction, the knives open in the direction in which the wheel is turned, and when the wheel is reversed the said knives are reversed automatically by coming in contact with the snow.

From the back plate G extends into the space I a cone K, terminating at its apex a suitable distance from the outer end of the space I, as is plainly shown in Fig. 1. From the apex of the cone K extend radial cutting-bars L, connected and riveted to the apexes of the paddles H. The cutting-bars L serve to cut up the snow as it enters the wheel and passes into the space I before traveling up the cone K to the paddles H.

The casing E is made cylindrical, open at the front, and provided with a bottom N, which extends a suitable distance below the rim of the casing, which latter is for this purpose cut out, as is plainly shown in Figs. 2 and 4. The 70 bottom N is somewhat shorter than the casing and is provided on the inside near each side with gussets O, leading up at their inner ends to the cut-out part of the rim of the casing, so that the snow can pass from near the 75 ground or track into the back of the casing at its bottom without obstructing or crowding the knives J and the front parts of the paddles H when they pass into their lowermost position on the revolving of the wheel.

The operation is as follows: When the car B is pushed forward, the shaft C is rotated by suitable means, so that the wheel D revolves within the casing E. When the wheel comes in contact with the snow, the rear 90 edges of the cutting-knives J are forced back, and the advancing edge is thrown forward to engage the snow, which is thus cut and thrown back between the paddles H. Snow which passes into the central space I is cut by the 95 cutting-bars L and travels over the sides of the cone K between the paddles H to throw the snow passing between the same from the knives and from the cone K through the outlet F to either side of the track at an angle 100 of about forty-five degrees. When it is desired to throw the snow out at the other side

of the track, then the motion of the wheel C is reversed, so that the motion of the wheel D is reversed, whereby the knives J are automatically reversed by the pressure of the 5 snow upon the cutting-edges. The wheel in revolving in the opposite direction causes the paddles II to throw the snow to the other side of the track. By constructing the wheel as described great strain at the center of the 10 wheel, caused by the snow separating and crowding it to the outside, is entirely avoided. As will be seen, the snow enters unmolested into the space I until it passes that point where the paddles are already filled with 15 snow cut by the knives J, the core of the snow thus passing into the space I and traveling up, after being cut by the cutting-bars L, the cone K to the rear of the paddles to be discharged, as previously mentioned. The 20 snow entering the casing E at the bottom N also passes to the rear of the casing to be operated on by the paddles II at their rear ends to be carried up and discharged through the opening F, as previously described. The 25 strain is thus removed from the center of the wheel, whereby the latter can operate with greater freedom and discharge the snow at a high rate of speed.

Having thus described my invention, I 30 claim as new and desire to secure by Letters Patent—

1. In a rotary snow-plow, a wheel comprising a back plate mounted to turn, a series of 35 paddles extending radially and at right angles from the front face of the said back plate, the apexes of the paddles terminating near the center of the back plate and arranged parallel to the axis of the wheel, so as to form a central space on the face of the said 40 back plate, and a cone secured with its base centrally on the face of the said back plate and extending freely into the said central space, substantially as shown and described.

2. In a rotary snow-plow, the combination, 45 with a casing, of a wheel mounted to turn therein and comprising a back plate, a series of paddles extending radially and at right angles from the front face of the said back plate, the apexes of the paddles terminating 50 near the center of the back plate and arranged parallel to the axis of the wheel, so as to form a central space on the face of the said back plate, and a cone secured with its base centrally on the face of the said back plate and 55 extending freely into the said central space, substantially as shown and described.

3. In a rotary snow-plow, a wheel comprising a back plate mounted to turn, a series of 60 paddles extending radially and at right angles from the front face of the said back plate and terminating near the center of the back plate to form a central space in the wheel, and reversible cutters held on the front ends of the said paddles, substantially as shown 65 and described.

4. In a rotary snow-plow, a wheel compris-

ing a circular back plate mounted to turn, a series of wedge-shaped paddles extending radially and at right angles from the face of the said back plate, the apexes of the paddles 70 terminating near the center of the back plate, so as to form a central space in the wheel, and reversible cutters held on the front ends of the said paddles, substantially as shown and described.

5. In a rotary snow-plow, a wheel comprising a back plate mounted to turn, a series of 75 paddles extending radially and at right angles from the front face of the said back plate and terminating near the center of the said back plate to form a central space in the wheel, a cone secured with its base centrally on the face of the said back plate and extending into the said central space, and reversible cutters held on the front ends of the said paddles, substantially as shown and described.

6. In a rotary snow-plow, a wheel comprising a circular back plate mounted to turn, a series of wedge-shaped paddles extending radially and at right angles from the face of 80 the said back plate, the apexes of the paddles terminating near the center of the back plate, so as to form a central space in the wheel, and radially-arranged cutters connecting with the apexes of the said wedge-shaped paddles 85 and located at or near the middle of the same, substantially as shown and described.

7. In a rotary snow-plow, a wheel comprising a back plate mounted to turn, a series of 90 paddles extending radially and at right angles from the front face of the said back plate and terminating near the center of the back plate to form a central space in the wheel, a cone secured with its base centrally on the face of the said back plate and extending into 95 the said central space, and radially-arranged cutters extending from near the apex of the said cone to the apexes of the said wedge-shaped cutters, substantially as shown and described.

8. In a rotary snow-plow, a circular casing open in the front and cut out at the bottom of its rim, and a horizontal bottom arranged below the cut-out part of the rim, substantially as described, so as to deliver the snow 105 near the ground to the rear of the casing, as set forth.

9. In a rotary snow-plow, a circular casing open in the front and cut out at the bottom of its rim, a horizontal bottom arranged below the cut-out part of the rim, substantially as described, so as to deliver the snow near 110 the ground to the rear of the casing, and gussets arranged in the sides of the said bottom and leading up at their inner ends to the cut-out part of the rim, substantially as shown and described.
